UNITED STATES PATENT OFFICE.

MELVIN JOSEPH FELLAND, OF GREAT FALLS, MONTANA.

SHIP-ARMOR.

1,270,715.

Specification of Letters Patent. Patented June 25, 1918.

Application filed May 7, 1917. Serial No. 166,906.

To all whom it may concern:

Be it known that I, MELVIN JOSEPH FELLAND, a citizen of the United States, and resident of Great Falls, in the county of Cascade and State of Montana, have invented certain new and useful Improvements in Ship-Armor, of which the following is a specification.

This invention relates to ships and has 10 more particular reference to an improved detachable armor therefor.

The invention has for its dominant object to provide detachable armor for protecting vessels while under way or idle from torpedoes discharged thereat by an enemy; the armor being so constructed and arranged with relation to the ship hull as to effectually engage and cause the discharge of the torpedo at a point distant from the ship hull 20 sides and further to permit the propelling and steering apparatus of the ship to be efficiently operated.

Another object of the invention is to provide the armor with buoyant means for floating the same and releasing the ship of the weight thereof at all times.

It is also an object of the invention to provide an armor of the character mentioned which can be readily and easily detached 30 from the ship and permitted to float on the surface of a body of water when the ship moves into a port for loading or unloading a cargo.

Other objects will be in part obvious and 35 in part pointed out hereinafter.

The invention accordingly consists in the features of construction, combination of elements and arrangements of parts which will be exemplified in the construction hereinafter set forth, and the scope of the application of which will be indicated in the following claims.

In the accompanying drawings, wherein is shown one of various possible embodiments of my invention—

Figure 1 is a fragmentary side elevation of a ship with the improved armor arranged thereon;

Fig. 2 is a fragmentary transverse section 50 through the ship and armor;

Fig. 3 is a detail in elevation of one of the various plates from which the armor is composed; and

Fig. 4 is a similar view showing one of 55 the plate connecting elements.

Similar characters of reference refer to

similar parts throughout the several views of the drawings.

Referring now more particularly to the drawings, it will be noted that I have shown 60 by way of illustration a fragment of a ship hull designated by the numeral 1, which hull has secured to its opposite side a series of upper and lower bearing brackets 2 and 3.

Supporting arms comprising sections of 65 piping so connected and arranged as to provide efficiently braced constructions are pivotally supported by the brackets 2 and 3, pivot pins 4 and 5 passing through the brackets and the engaged portion of the supporting arms which are generally indicated by the numeral 6. Collars 7 are carried upon the lower extremities of the various arms 6 and receive therethrough parallel longitudinally extending pipes or rods 8, which pipes, 75 obviously, serve as means for rigidly connecting the lower ends of the supporting arms and preventing relative movement of the same while the ship is under way. Other bracing means in form of truss rods 9 are 80 arranged between the supporting arms 6 and have their opposite ends engaged with eyes 10 and 11 formed upon the lower ends of the said bracing arms and the bearing brackets 2, respectively. The adjacent end 85 of the truss rods, which as will be noted, are made in sections, are screw threaded and engaged by ordinary turnbuckles 12 in order that the truss rods may be properly adjusted to maintain the supporting arms 6 in the 90 desired position with relation to the sides of the ship.

Pontoons 13 conforming to the contour of the ship hull are provided and are secured to the bases of the various supporting arms 95 by elongated strips 14. Reinforcing casings 15 are arranged about the pontoons 13 and have their adjacent ends flanged as at 16 to provide a longitudinally extending rib, while a second rib 17 is formed in proximity 100 of the flanges 16 by crimping a portion of the casing. Within the outer sides of the pontoons 13 steels 18 are secured and are formed integral with certain of the connections of the piping forming the supporting 105 arms 6, thereby shielding the same from projectiles which may be discharged thereat in an effort to disable the same.

A plurality of armor plates 19 are employed in the forming of the armor for the 110 ship and have series of notches 20 formed in their side edges adapted to be alined with

complementally disposed openings 21 formed in connecting elements or strips 22 for receiving rivets therethrough. The plates 19 and strips 22 may be and preferably are 5 formed of high grade steel or other metal which will successfully withstand the force of torpedo explosions. A plurality of rings 23 are passed through suitable openings formed in the upper portions of the plates 10 19 and the strips 22 into engagement with other openings formed in the flanged portions 16 and the rib 17, it being noted that a pair of the sectional armor plates are provided and are arranged in oppositely disposed 15 relation upon the pontoons 13. Thus, the ship is provided with primary and secondary armor adapted to intercept the torpedo and to cause its explosion at a point distant from the sides of the ship. By 20 maturely exploding the torpedo, the water in the intervening space between the primary and secondary armor plates will fully absorb the force of the resultant explosion and will cause the same to be spent in the 25 line of least resistance, which would be upwardly, since, it is not presumed that the primary and secondary armor plates will stand the force of an explosion but that the same will, however, have sufficient 30 weight to cause the discharge of the torpedo at a safe distance from the sides of the ship. Furthermore, if the primary armor plate is penetrated or demolished, it will be understood that the secondary plate 35 will serve as an efficient buffer for the torpedo or projectile, the velocity of which has been greatly decreased by its engagement with the primary armor plate.

When a ship carrying my improved armor 40 moves into a port, the armor may be readily detached from the sides thereof by removing the pivot pins 4 and 5 from the brackets 2 and 3, whereupon the pontoons 13 will serve to float the armor. Upon leaving the 45 port, the ship is guided between the pontoons and the pivot pins 4 and 5 again connected with the brackets 2 and 3. It is to be also understood, in this connection, that a suitable truss rod, not shown, is provided 50 and has its opposite end connected to the forward ends of the pontoons 13 and is adapted to be engaged by the prow of the ship when the same is arranged between the pontoons.

55 From the foregoing, it will be appreciated by workers in the art, that with my improved armor, a ship may safely navigate

bodies of water without danger of being wrecked by the discharge of torpedoes thereonto. Further, due to the manner in which 60 the primary and secondary armor plates are suspended from the pontoons 13 steering of the ship will be permitted and rolling of the same with the waves also allowed, thereby preventing the shipping of quantities of water. Since the head on resistance 65 of the armor when the ship is under way is but slight, inasmuch as the pontoons serve to support the same, the speed of the ship will not be materially decreased but will 70 be stabilized by reason of the arrangement of the said pontoons upon either side thereof.

Manifestly, the construction shown is capable of considerable modification and 75 such modification as is within the scope of my claims, I consider within the spirit of my invention.

I claim:

1. A ship armor including a plurality of 80 trussed supporting arms detachably secured to the sides of the ship, pontoons secured to the lower portions of said arms, shields arranged upon the outer sides of said pontoons, and oppositely disposed armor plates 85 pivotally engaged with the pontoons and extending below the bottom of the ship.

2. A ship armor including a plurality of 90 braced supporting arms detachably secured to the sides of the ship, rigid means engaged with the lower extremities of said arms for bracing the same in spaced apart relation, truss rods engaged with the arms, pontoons carried upon the lower portions of 95 said arms and conforming to the contour of the ship hull, and a plurality of spaced armor plates loosely suspended from the pontoons and extending below the bottom of the ship.

3. A ship armor including a plurality of 100 substantially triangular supporting arms detachably secured to the sides of the ship, rigid means engaged with the bottoms of the arms for bracing the same in spaced apart relation, adjustable truss means engaged with said arms, pontoons carried by the arms, shields arranged upon the outer sides of said pontoons, and a plurality of 105 spaced armor plates loosely suspended from the pontoons.

In testimony whereof, I affix my signature hereto.

MELVIN JOSEPH FELLAND.
